(57) **CLAIM**

Thr ornamental design for a rotatable tool handle, as shown and described.

DESCRIPTION

FIG. 1 is a side perspective view of one embodiment of a handle showing my new design;

FIGS. 2 and 3 are respectively top plan and side elevation views thereof, the respective opposite sides being mirror images of FIGS. 2 and 3;

FIG. 4 is a section view taken on the line 4—4 of FIG. 3; FIGS. 5 and 6 are respectively right end and left end elevation views of FIG. 3;

FIGS. 7 and 8 are respectively side elevation and top plan views showing a second embodiment thereof, the only difference being the addition of the flange on the left end of FIGS. 7 and 8, it being understood that all other surfaces are the same as those of the first embodiment, and the respective opposite sides being mirror images of FIGS. 7 and 8; and, FIG. 9 is a section view taken on the line 9—9 of FIG. 8.
